UNITED STATES PATENT OFFICE.

HENRY H. COLLINS, OF PITTSBURG, PENNSYLVANIA.

TUBE-EXPANDER.

SPECIFICATION forming part of Letters Patent No. 223,840, dated January 27, 1880.

Application filed December 10, 1879.

To all whom it may concern:

Be it known that I, HENRY H. COLLINS, of Pittsburgh, in the county of Allegheny and State of Pennsylvania, have invented a new and useful Improvement in Tube-Expanders; and I do hereby declare that the following is a full and exact description thereof, reference being had to the accompanying drawings, and to the letters of reference marked thereon.

10 My invention relates to an improvement in tube-expanders, the same being an improvement upon the tube-expander of William Thomson, of Glasgow, Scotland, for which English Letters Patent were granted him April 15, 1874, No. 1,430, my improvement consisting in placing the recesses for the reception of the expanding-rollers at an acute angle to the axis of the mandrel.

To enable others skilled in the art to which 20 my invention is most nearly connected to make and use it, I will proceed to describe its construction and operation.

In the accompanying drawings, which form part of my specification, Figure 1 is a side elevation of my improvement in tube-expanders. Fig. 2 is a vertical and longitudinal section of the same at line *x* of Fig. 3. Fig. 3 is a transverse section of the same at line *z* of Fig. 1. Fig. 4 is a side view of one of the rollers.

30 In the accompanying drawings, *A* represents the mandrel, in which is pivoted a roller, *B*, journaled at *g* and *h*, and is held in position by means of screw-threads *i* and screw-nut *j*, which is prevented from turning by a pin, *k*, 35 or by a jam-nut, as indicated by the dotted lines *o* in Fig. 1. The mandrel is made hollow and furnished with a number of recesses, *D*, which are arranged longitudinally at an acute angle to the axis of the mandrel *A*. In 40 the recesses *D* are journaled, at *e* and *f*, tapering rollers *C*, the inner surfaces of which impinge on the roller *B*. The rollers *C*, at the end having the smaller diameter, are tapered at a different angle from that of the body of 45 said rollers, as indicated at *p*. By thus tapering the rollers *C*, as at *p*, a lead is formed for the body of said rollers, and the forming of an inward-projecting ridge is prevented.

By arranging the recesses *D* at an acute angle to the axis of the mandrel *A*, the bearing

ends of the rollers *C* will be at an acute angle to the axis of the roller *B*, whereby the desired feed of the expander is obtained and all undue strain and friction of the journals *e* and *f* of the rollers *C* is avoided, causing the expander in all its parts to work smoothly in the operation of expanding the tube. The ends of the journals *e* of the rollers *C* are covered by cap-piece *l*, which is held in position by the journal *h* of the roller *B* and the screw-nut *j*, 55 as shown in Figs. 1 and 2.

The operation of my improvement is as follows: The tube being placed in the boiler-head in the usual manner, the small end of the expander is placed in the end of the tube. The operator then places a wrench upon the end *q* of the roller *B*, and turning it to the right will cause the rollers *C* to turn to the left, the outer surface of the rollers impinging upon the inner walls of the tube, and their inner 70 surface impinging upon the roller *B*, the latter, *B*, revolving the former, *C*, by frictional or tractive action of the one upon the other. The inclination of the rollers *C* with relation to the axis of the mandrel *A*, the latter acting as a guide, feeds the expander into the tube, the rollers *C* performing the function of a series of screw-threads. When the expander has entered the tube sufficiently to give it the desired expansion, the operator 75 places a wrench upon the square *r* on the mandrel *A*, turning it sufficiently to release the expander in the tube, which is then withdrawn. The roller *B* may be turned through 80 the medium of levers, as indicated by the dotted lines *n*, (shown in Fig. 1,) placed in the opening *m*.

The advantage of my improvement consists in avoiding friction upon the journals of the rollers *C* by arranging them in the manner as 90 hereinbefore described and giving to the part *p* of the rollers *C* a different angle or taper from that of the body, said tapers forming a lead for the body of the rollers, and preventing the formation of ridges upon the inner walls 95 of the tube, which is a very important feature, for such ridges form impediments to a free draft and catch fine particles of fuel, which, becoming ignited, unduly heat the flues around said ridges, causing a wasting and de- 100

structive action, which soon destroys the tube; and by arranging the angles of force of the rollers C with relation to the axis of rotation of the roller B and mandrel A, the expander as a whole will work smoothly, and without any dragging and undue frictional action upon the inner wall of the tubing in the process of expanding it.

Having thus described the nature, construction, and operation of my improvement, what I claim is—

In a tube-expander, the combination, with the roller B, of the mandrel A, provided with recesses D, for the reception of the expanding rollers, arranged at an acute angle with relation to the axes of said mandrel and roller B, substantially as and for the purpose set forth. 15

HENRY H. COLLINS.
